CLAIM

The ornamental design for underpants as shown and described.

DESCRIPTION

FIG. 1 is a front perspective view of the underpants showing our new design displayed for illustrative purposes as they would appear worn on a form representing a partial human figure;

FIG. 2 is a back perspective view of the underpants displayed for illustrative purposes as they would appear worn on a form representing a partial human figure;

FIG. 3 is a front view of our new design;

FIG. 4 is a back view thereof;

FIG. 5 is a right side view thereof with the left side view being a mirror image;

FIG. 6 is a top view thereof;

FIG. 7 is bottom view thereof;

FIG. 8 is a front view of the underpants showing our new design in an alternative embodiment;

FIG. 9 is a back view according to the embodiment of FIG. 8; and,

FIG. 10 is a bottom view of the design with the underpants in an expanded or outspread position to show the bottom inseam, according to the embodiment of FIG. 8. The inseam design also corresponding to the inseam structure of the embodiment of FIGS. 1-7 save for the diagonal shading lines.

The diagonal shading lines in the drawings reflect a surface containing asperities having a contrasting texture from the other regions of the design.

1 Claim, 10 Drawing Sheets
